DESIGN FOR AN ASH TRAY OR SIMILAR ARTICLE

Herman Rubenstein, New York, N. Y.

Application March 2, 1935, Serial No. 55,691

Term of patent 7 years

To all whom it may concern:

Be it known that I, Herman Rubenstein, a citizen of the United States of America, residing at New York city, Bronx County, State of New York, have invented a new, original, and ornamental Design for an Ash Tray or Similar Article, of which the following is a specification, reference being had to the accompanying drawing, forming a part hereof, wherein the figure represents a perspective view of an ash tray showing my new design.

I claim:—

The ornamental design for an ash tray or similar article substantially as shown.

In witness whereof, I have signed this application.

HERMAN RUBENSTEIN.
